UNITED STATES PATENT OFFICE.

WILLIAM V. WILSON, OF NASHVILLE, TENNESSEE.

DESIGN FOR A RULER.

SPECIFICATION forming part of Design No. 25,261, dated March 24, 1896.

Application filed February 10, 1896. Serial No. 578,801. Term of patent 7 years.

To all whom it may concern:

Be it known that I, WILLIAM V. WILSON, residing at Nashville, in the county of Davidson and State of Tennessee, have invented and produced a new and original Design for a Ruler, of which the following is a specification, reference being had to the accompanying drawings, in which—

Figure 1 is a perspective view of a ruler embodying my design, and Fig. 2 is a cross-section thereof on the line 2-2 of Fig. 1.

My design consists in the ornamental configuration of the handle and the ruler-blade, which configuration comprises a blade A, having one top edge beveled downward, as at a , and the opposite under edge beveled upward, as at a' . Centrally the blade has a handle ornamentation B, the upper end, b , of which is made circular-like in cross-section and ter-

minates at the opposite sides in concaved portions $b' b'$, which in turn terminate in abrupt beveled representation $b^2 b^2$, which merge into the top of the ruler-face. Viewed in perspective the upper end or portion b of the handle has its ends beveled at b^6 and merge through curvatures b^3 with extensions b^4 , the ends of which merge into the ruler-top and which in turn have their tops flattened, as at b^5 .

Having thus described my invention, what I claim, and desire to secure by Letters Patent, is—

The design for a ruler substantially as shown and described.

WILLIAM V. WILSON.
